UNITED STATES PATENT OFFICE

WENDELL H. CLARK, OF KENILWORTH, ILLINOIS

THIRD RAIL SELECTOR FOR TOY RAILROADS

Application filed December 26, 1929. Serial No. 416,313.

This invention relates to toy electric railroads and its object is to enable two or more trains to be run at the same time on a main track, or on a main track and side tracks, 5 switches, cross-overs and the like, independently of each other and under separate control.

And a further object of the invention is to provide a toy electric train system including 10 a plurality of third rails and engines having contact shoes adapted for selective engagement with said third rails so that a plurality of trains may be run on the same track independently of each other and under separate 15 control.

In the accompanying drawing I have illustrated a selected embodiment of the invention wherein

Fig. 1 is a transverse sectional view showing as much of an engine as is necessary to illustrate the invention.

Fig. 2 is a sectional view on the line 2—2 of Fig. 1.

Fig. 3 is a bottom plan view of the engine 25 shown in Figs. 1 and 2.

Figs. 4, 5 and 6 are detail views illustrating modifications of the invention.

Referring to the drawing 8 represents generally a track and 9 an engine to run on the 30 track. Third rails 10 and 11 are mounted side by side on the track and are suitably insulated therefrom. Electric contact is made in any well-known way between the engine and one of the third rails by means of a shoe 35 carried by the engine. In the form shown the shoe comprises a spring plate 12 having a transverse slot 13 to receive screws 14 or other suitable means for fastening the plate to the engine. The plate carries contact rollers 15 at its ends adapted to make electric contact 40 with one of the third rails. It is well known in the art to provide engines with contact shoes for this purpose and it will not be necessary in these specifications to describe the 45 electric connections. Heretofore, however, it has been the practice to provide a single third rail on the track and to secure the shoe in fixed position on the engine but my invention provides for two or more third rails on 50 the track and also provides for adjusting the

shoe so that it can be made to contact with any one of these third rails. The adjustment may be effected by loosening the screws 14 and shifting the shoe bodily and transversely of the engine into proper registration with the 55 third rail with which it has been selected to contact, and then tightnening the screws to secure the shoe rigidly in its adjusted position, but I prefer to avoid the necessity of manipulating the screws and to utilize them for guiding the shoe in its adjustment, and I provide 60 projections which may be in the form of indentations 16 on the plate 12 to engage recesses 17 in the engine for retaining the shoe in its adjusted position. This enables the adjustment to be made easily and quickly and as often as desired without the use of tools. The invention enables engines to be provided with standard shoes all mounted in the same manner but capable of adjustment to make 65 contact with any one of a plurality of third rails on the track and in this way two or more trains may be run on the same track independently of each other and under separate 70 control electrically connected with the third 75 rails. I have described the shoe as mounted on an engine because this is where the shoe is commonly placed in toy electric railroads but it may be mounted on the tender or on any of the cars and it will be understood that in referring to the engine as carrying the contact shoe I mean to include any part of the train upon which the shoe may be mounted. Thus a toy electric train system may be provided 80 comprising a main track with side tracks, 85 switches, cross-overs and other additions like regular train systems or in any desired combinations, and a number of trains may be run on the tracks independently of each other and under separate control thereby increasing 90 the interest and amusement to be derived from the operation of toys of this kind.

I may provide a plurality of third rails 18 mounted upon an insulated support 19 and a shoe 20 adapted for adjustment to engage 95 any one of said third rails, Fig. 4; or I may provide a plurality of third rails 21 mounted on and insulated from a support 22, and a shoe 23 adapted for adjustment to make contact with any one of said third rails, Fig. 5; or 100

I may provide a shoe 24 with two contact rollers 25 arranged side by side in separate constant engagement with third rails 26, Fig. 6, the rollers being electrically connected with 5 a switch 27 which can be set for operating the train from one or the other third rail. And I may make other changes in the form, construction and arrangement of parts of my invention to adapt it to different embodiments, 10 or for other purposes, within the scope of the following claims:

I claim:

1. In a toy electric railroad, the combination of a plurality of third rails, an engine, a 15 shoe, means for adjustably securing the shoe to the engine for contact with any of said third rails, and means on the engine for determining the position of said shoe to engage said shoe with a selected one of said third 20 rails.
2. In a toy electric railroad, the combination of a plurality of third rails, an engine, and a shoe adjustably mounted on the engine for contact with any of said third rails, said 25 shoe comprising a plate having a transverse slot therein, means arranged in said slot for holding the shoe on the engine and for guiding the shoe in its adjustment, and means for holding the shoe selectively in adjusted 30 position on the engine.
3. In a toy electric railroad, the combination of a support having a pair of third rails arranged thereon in opposition to each other and another third rail intermediate the opposed third rails, an engine, a shoe mounted on the engine, and means for adjusting the shoe for contact with any one of said third 35 rails.

WENDELL H. CLARK.
